HAIRPIN

Edward D. Davis, Chicago, Ill., assignor to The
Boye Needle Company, Chicago, Ill., a corpora-
tion of Illinois

Application May 20, 1936, Serial No. 80,899
Renewed July 28, 1937

11 Claims. (Cl. 132—50)

This invention relates to a hairpin.

An object of the invention is to provide a hairpin so shaped as to greatly diminish the visibility of the hairpin. A further object is to provide a hairpin provided throughout with lateral notches or crimps which cause the pin to remain in position in the hair. A further object is to provide a laterally-crimped hairpin with roughened interior surfaces. A still further object is to provide a clip hairpin having notches or crimps in its legs, the crimps or notches being vertically aligned. Other specific objects and advantages will appear as the specification proceeds.

15 The invention is illustrated, in preferred embodiments, by the accompanying drawing, in which—

Fig. 1 is a plan view of a pin embodying my invention; Fig. 2, a side view in elevation; Fig. 3, 20 a plan sectional view, the section being taken as indicated at line 3 of Fig. 2; Fig. 4, a plan view of a modified form of pin; and Fig. 5, a view similar to Fig. 3 of a hairpin, the inner surface of the head being provided with superficial roughening.

25 In the illustration given in Figs. 1, 2 and 3, 10 and 11 designate the upper and lower legs of a clip hairpin, the legs being connected by an integral bend 12. The inner surfaces of one or both legs are superficially roughened, as indicated by 30 the numeral 13. The legs and bend 12 are provided with inwardly extending notches or indentations 14. Such notches 14 form laterally extending projections or crimps 15.

The legs 10 and 11 are preferably of uniform 35 pliability or strength, so that when it is desired, the legs may be spread apart to form the normal type of hairpin shown in Fig. 4. This hairpin is, however, characterized by the fact that it has flat legs 10 and 11, which are provided interiorly 40 with roughening 13. This hairpin is further new, in that it has lateral crimps or notches extending along its sides and bend or head.

For many years, it has been known that one 45 of the largest defects of the modern clip hairpin lies in the fact that its head or integral bend has to be prominently and obtrusively displayed. When the hairpin is applied, it is concealed to a substantial extent, except as to the bend or head. This portion of the pin is practically always in full view and its plain flat or round shape 50 renders it sharply conspicuous.

I have found that the above defect can be substantially overcome by providing a hairpin with lateral crimps or notches running not only along 55 the legs of the pin, but also along the bend or

head. This structure permits less metal stock to be used, with the result that a substantially thin pin is made stiff enough to serve, while at the same time the lateral crimps tend to make the head or bend less visible. I have further found that a more extensive gripping surface is afforded by the lateral crimps when they are provided with superficial roughening. The roughened clamping surfaces cooperate with the notches to hold strands of hair securely within the pin.

In the modification shown in Fig. 4, the construction is substantially identical with that shown in Fig. 1, except that the lateral notches or crimps are omitted from the head 12a.

The pins, as heretofore described, may be formed either from flat metal strips or from round wire. If desired, the notches may be formed by cutting away metal from the sides of the pin. Also, if desired, the notches may be formed by starting with a round wire, bending the wire laterally to form crimps, and then flattening the entire strip, or the desired portion thereof, to the shape shown in the figures. While, if desired, the notches of the two legs need not be brought into alignment, I prefer to have the notches in alignment, in order to increase their effectiveness for locking the pin in the hair.

The ends of the pins may be slightly spread apart to facilitate the opening and spreading of the pin.

The superficial roughening or knurling on the inner surfaces of the pin may be formed as set out in my Patent No. 1,848,771, March 8, 1932. I have found, however, that the roughening is considerably more effective when lateral crimps are employed because of the increase in gripping surface and because the roughened surfaces co-operate with the notches to lock the hair within the pin.

In the operation of the pin shown in Figs. 1 to 3, inclusive, the ends of the pin may be grasped to spread the legs apart and to permit their insertion in the hair. As the legs come together, the locks of hair are gripped between the legs. It is found that the strands of hair adjacent the notches 14 extend upwardly and downwardly about the notches and engage the crimps or shoulders 15.

In the modification shown in Fig. 5, I provide an ordinary hairpin with interior roughened surfaces extending not only along the legs but also about the head. Preferably this form of pin is provided with flat legs and also with a flat head although other shapes may be employed. The

superficial roughening tends to lock the head itself firmly within the hair and prevents it from protruding.

The new pin has the extremely important advantage, in that it is substantially invisible in the hair. Furthermore, the lateral projections cooperate with the roughened surfaces to provide new means for holding the pin securely in position.

10 While, in the foregoing description, I have set forth certain structures, it will be understood that they may be modified considerably, each being modified to include changes shown in the other structures, and by other modifications 15 which are obvious to one skilled in the art.

The foregoing detailed description has been given for clearness of understanding only, but the appended claims should be construed as broadly as permissible, in view of the prior art.

20 I claim:

1. A hairpin having two legs connected by an integral bend, said bend and at least one leg being provided with lateral crimps.

2. A hairpin having two legs connected by an 25 integral bend, said bend being provided with lateral crimps.

3. A hairpin having two legs connected by an integral bend, said bend and at least one leg being provided with lateral crimps, and said legs 30 being maintained by said bend normally in a contacting position.

4. A hairpin having two legs connected by an integral bend, said bend and at least one leg being provided with lateral crimps, and said legs

being maintained by said bend normally in a contacting position, and at least the inner surface of one of said legs being superficially roughened.

5. A hairpin comprising a pair of legs connected by an integral bend, said legs and bend being laterally crimped and said legs alone having 5 their inner surfaces roughened.

6. A hairpin comprising two legs connected by an integral bend, each of said legs having 10 lateral notches formed in its side, the notches of one leg being aligned with the notches of the other leg.

7. A clip hairpin comprising two legs connected by an integral bend, each of said legs having 15 lateral notches formed in its sides.

8. A clip hairpin comprising two legs connected by an integral bend, each of said legs having lateral notches formed in its sides, and at least 20 one of said legs having its inner surface superficially roughened.

9. A clip hairpin comprising two legs connected by an integral bend, each of said legs having portions of its side provided with inwardly extending notches, said legs being of uniform width 25 throughout.

10. A clip hairpin comprising two legs connected by an integral bend, said legs being provided with a series of pairs of aligned notches and being of substantially equal length. 30

11. A hairpin comprising: two legs connected by an integral bend, said bend being provided with superficial roughening.

EDWARD D. DAVIS.
